UNITED STATES PATENT OFFICE.

CHARLES PEARSON, OF CHICAGO, ILLINOIS, ASSIGNOR TO INTERNATIONAL HARVESTER COMPANY, A CORPORATION OF NEW JERSEY.

SHOCK GATHERER.

Application filed April 10, 1919. Serial No. 289,080.

To all whom it may concern:

Be it known that I, CHARLES PEARSON, a citizen of the United States, residing at Chicago, in the county of Cook and State 5 of Illinois, have invented certain new and useful Improvements in Shock Gatherers, of which the following is a full, clear, and exact specification.

This invention relates to machines for 10 gathering and transporting shocks of grain or other material.

The invention has among its objects to facilitate the gathering and transporting of shocks of grain and to provide a construction having a maximum capacity for the size 15 of the structure, and moreover, a construction that may be operated by power.

A further object is to provide power operated connections for tilting, raising and 20 lowering the gathering means, and also to control these power connections in such a manner that the gathering means may be tilted to various angles, and also in such a manner that the rear end of the gathering 25 means may be raised off the ground while the front end is maintained substantially in contact with the ground.

A still further object is to provide supporting and steering means for a device of 30 the character described, this supporting and steering means being so mounted that the said means will not be thrown out of control when the machine is started either forwardly or rearwardly.

With these and other objects in view, 35 which will appear as the description proceeds, I have embodied my invention in a practical construction which has been illustrated in the accompanying drawings, and in these drawings,—

Figure 1 is a top plan view of the gathering mechanism;

Fig. 2 is a front elevation of the construction shown in Fig. 1, one side of the gathering means being shown in folded position and the rake or gathering means being shown in this view in its lower position;

Fig. 3 is also a front elevation of the construction shown in Fig. 1, the rake or gathering means being shown in its raised position and the sides of the rake being folded;

Fig. 4 is a side elevation of the front end of my improved device;

Fig. 5 is a side elevation of the rear end 55 of the shock gatherer showing the tilting lever

mechanism and the steering mechanism, Figs. 4 and 5 taken in conjunction with each other showing in side elevation the entire machine;

Fig. 6 is a plan view of the rear portion 60 of the construction shown in Fig. 5;

Fig. 7 is a front view of the steering wheel;

Fig. 8 is a partial sectional view of the steering wheel shown in Fig. 7;

Fig. 9 is a front elevational view partly 65 in section showing the racks carried by the rake frame and the clutch and pinion mechanism for raising and lowering the frame;

Fig. 10 is a side elevation of one of the 70 racks shown in Fig. 9 and also of the pinions which mesh with said rack;

Fig. 11 is a side elevation partly in section showing the pawl and ratchet control 75 for the clutch mechanism shown in Fig. 9;

Figs. 12 and 13 are sectional views through 80 the clutch mechanism that controls the raising and lowering of the rake, Fig. 12 showing the driving pawls out of contact with the constantly rotating portion of the clutch, and Fig. 13 showing the pawls in contact with said member;

Figs. 14 and 15 are side elevations and end 85 elevations respectively, of one of the pawl members shown in Figs. 12 and 13;

Fig. 16 is a detail view partly in section showing the pawl controlling means for the clutch and the ratchet wheel which operates therewith;

Figs. 17 and 18 are front and side elevations 90 respectively, of the ratchet wheel and the pawl controlling member shown in Figs. 12 and 13;

Figs. 19 and 20 are front and side elevations 95 respectively, of the supporting bracket which pivotally supports the pawls;

Fig. 21 is a view in elevation of a portion 100 of the power driven rake controlling shaft illustrating particularly the ratchet and pawl mechanism which retains the rake or gathering means in elevated position and also the brake mechanism which controls the lowering of the gathering means;

Fig. 22 is a sectional view of the construction 105 shown in Fig. 21 taken through the ratchet and pawl mechanism;

Fig. 23 is a sectional view of the brake mechanism illustrated in Fig. 21;

Figs. 24 and 25 are detail views illustrating 110 the pawl construction shown in Fig. 21

and the mounting of the pawl and brake band also shown in Fig. 21;

Fig. 26 is a sectional detail view illustrating the connection of the chains which control the tilting of the gathering means to the frame of the gathering means, this construction also being shown in Fig. 4; and

Figs. 27 and 28 illustrate in side and end elevation a section of the guiding member which controls and guides the sides of the gathering means as they are folded.

My improved shock gatherer consists, briefly, of a raking member having longitudinally extending lines, the frame of this raking member being vertically adjustable upon a carrying frame. The raking member frame is supported upon two carrying wheels and a power shaft is operatively connected to one of the carrying wheels. This power shaft is provided with suitable clutch mechanism and a plurality of pinions, the pinions meshing with vertical racks carried by the frame of the raking member and operating to raise and lower the racks and the frame of the raking member as the clutch mechanism is operated to connect the power shaft with the driving wheel. Lever mechanism is also carried by the supporting frame and is connected to the rake frame in such a manner that the rake may be tilted to the desired angle. The supporting frame for the raking member is provided with a rearwardly extending pole, the rear end of which is supported upon a steering wheel and provided with a vertically extending shaft by means of which the wheel support may be rotated on a vertical axis and the shock gatherer may be steered. The construction last referred to is similar to that found upon headers and sweep rakes.

Referring now to the drawings, the supporting frame for the rake frame includes a longitudinal pole member 30 having a bracket 31 secured to its rear end, this bracket being provided with spaced lugs 32 in which is journaled a vertical shaft 33 having an upper squared portion 34. The portion 34 of the shaft 33 has mounted thereon a bracket 35 which carries a forwardly projecting handle 37, having a seat 36 mounted thereon, this construction being similar to that found on headers, as above stated.

The rear end of the pipe or pole member 30 is supported by means of a supporting and steering wheel 38 pivotally mounted on an axis 39 carried by U-shaped bracket 40. The bracket 40 is pivoted on a horizontal pivot pin 41 carried at the lower end of a bracket 42 which is mounted on the shaft 33, as clearly illustrated in Fig. 5. The U-shaped bracket 40 has formed thereon a bridge portion 43 which is disposed intermediate the rim of the wheel and the pivot pin 41, and is adapted to contact with down-

wardly extending spaced lugs 44 formed on the lower end of the bracket 42.

In Fig. 5 the steering wheel 38 and bracket 40 are shown in the position which they assume after the machine has been started and is being propelled around the field. When it becomes necessary for any reason to back the machine, the wheel 38 and bracket 40 will be moved to the position shown in dotted lines in Fig. 8, the bracket 40 swinging on the pivot 41. It will be readily understood that as the machine is backed there will be a tendency for the wheel 38 to move, either on the vertical pivot or upon its horizontal pivot 41, and in the absence of the pivotal connection between the bracket 40 and the bracket 42, the wheel 38 will be swung on the vertical pivot and the driver,—unless special care were taken—would be thrown from the seat.

In my construction, however, the pivoting of the bracket 40 on the pin 41 prevents the rotation of the wheel 38 on the vertical pivot, since this initial movement is taken up by swinging the wheel to the dotted line position shown in Fig. 8.

The construction just described operates in an exactly similar manner when the machine has been backed and is started forward again.

The front end of the pipe 30 has secured thereto a pair of brace members 45 secured at their inner ends to the pipe and diverging for a certain distance each side of the pipe, the outer ends of these members being bent forwardly and disposed in parallel relation as shown at 46. The portions 46 of the brace members 45 are connected by means of a transverse frame member 47, and the front ends of the portions 46 are connected to the pipe 30 by means of additional brace members 48, these members being connected to the transverse member 47 by brackets 49. The front end of the pipe 30 has secured thereto forwardly extending 100 brackets or frame members, 50, which carry at their front ends vertical brackets 51 provided with horizontal journals through which extends the power shaft 52. Vertical brackets 53 are also secured to the front 110 ends of the portions 46 of the brace members 45, and these brackets are also provided with horizontal journals which support the shaft 52.

The shaft 52 is supported at its outer ends 120 by the carrying wheels 54, one of these wheels being provided with power connections for driving the shaft as hereinafter described.

The rake frame comprises transverse 125 frame members 56 preferably formed of angle iron as shown in Fig. 4, these members being braced by means of diagonal truss members 57 as shown in Figure 1. The vertical portion of the rake frame comprises 130

vertically extending members 58, a series of these members being secured at their lower ends to the front transverse frame member 56 as shown in Fig. 2. A plurality of horizontal frame members 59 are employed to strengthen the vertical frame, and these members are secured at their opposite ends to certain of the vertical frame members 58, this construction being also shown in Fig. 2. Diagonal braces 60 are provided to strengthen the rake frame, these members extending between the horizontal and vertical frame members and being secured at their upper ends to inclined frame members 61, which are carried by the vertical members 58 at their upper ends, a bracket 62 connecting the members 61 at their upper ends.

A plurality of longitudinally extending rake tines 63 are secured to the horizontal frame members 56, preferably by means of U-shaped bolts 64. The main portion of the rake is mounted between the carrying wheels, but in addition to this portion I have provided a supplemental folding section outside of each of the carrying wheels.

The construction of these folding sections of the rake is illustrated in Figs. 1, 2 and 3, each section including transverse members 65 connected by diagonal braces 66, and having forwardly extending tines 67 exactly similar to the tines 63. Inclined frame members 68 and 69 are pivoted at their lower ends to the outer ends of the frame members 65 as shown at 70, and have their upper ends rigidly connected together by means of a plate 71. A transverse bolt 72 extends through the upper ends of the members 68 and 69 and pivotally connects them to a guiding member 73 which is provided with an angular slot 74 that fits over the upper frame member 61 of the rake frame as shown in Figs. 27 and 28.

The frame members 68 and 69 have pivotally secured thereto at their upper ends a bracket 75 which is connected by means of a cable 76 extending over an idler 77 to a winding drum 78 fixed to the power shaft 52, and as the shaft is rotated the cable 76 will be wound on the drum and the supplemental rake frame members will be folded as shown in Fig. 3. If desired, a clutch may be interposed between drum 78 and shaft 52 to enable the operator to disconnect the drum from the shaft at will. The inclined frame member 69 of the supplemental rake frame has secured to its lower end a bracket 78 which supports a supplemental rake tine 79, the rear end of which is bent downwardly and secured to the diagonally positioned member 68 as shown in Figs. 2 and 3. This supplemental tine retains the bundles on the supplemental rake frame. Hooks 80 are carried at the upper ends of the outer vertical frame members 58 and cooperate with

eye-bolts 81 to hold the supplemental rake frames in their extreme folded position for transport, as shown in Fig. 2. It will be understood that, in the particular construction illustrated, as the rake frame is raised by means of the power derived from the shaft 52 and the cables 76 are wound on the drums carried by said shaft, the supplemental rake frames are folded only to the position shown in Fig. 3, and that the supplemental rake frames are folded to the extreme folded position shown in Fig. 2 only for transport, said supplemental frames being manually lifted to that position. However, by simply changing the size of drum 78' the supplemental frames may be completely folded by the power shaft and drum. Shield members 82 are secured in any suitable manner to the supporting frame and extend around the front of the carrying wheels 54 thereby preventing any hay or grain from coming in contact with the carrying wheels.

The driving connections and the clutch mechanism between the power shaft and the driving wheels will be next described.

As illustrated in the drawings, a single driving wheel is connected to the power shaft, but if desired both wheels may be so connected.

Turning now to Figs. 9 to 20, the clutch mechanism will be explained. As shown in Fig. 9, the hub 83 of one of the wheels 54 has secured thereto or formed integrally therewith, a constantly rotating clutch member 84, having an outwardly extending annular flange portion 85. The portion 85 of the constantly rotating clutch member 84 has formed thereon inwardly extending lugs 86 adapted to be engaged by rollers 87 rotatably mounted in triangular shaped pawl members 88 pivoted at 89 to outwardly projecting apertured lugs 90 carried by a sleeve member 91 which is keyed to the power shaft 52. This construction is illustrated in detail in Figs. 9, 12, and 13.

The particular construction of the pawls 88 is illustrated in Figs. 14 and 15 and from said figures it will be seen that the pawls, as above stated, are triangular in outline, outwardly extending lugs 90' being formed thereon, springs 91' engaging the lugs 90' and recesses 92 formed in the pawl supporting sleeves 91. The pawls are also provided with laterally extending or offset lugs 93 which engage notches 94 formed in the outer ends of a pawl controlling bracket 95 journaled on an extension 96 of the sleeve 91 which forms the support for the pawls. The pawl controlling member 95 has formed integrally therewith a wheeled member 97 having a series of peripheral notches 98, this notched wheel forming a ratchet wheel. The springs 91' above referred to tend to swing the pawls 88 about their pivots 89 to the position shown in Fig. 12, in which

position the rollers 87 are out of engagement with the lugs 86 carried by the constantly rotating member 84.

The method of manipulating the pawl 99 controlling member 95 and the ratchet wheel 97 will next be described.

A pawl 99 is secured to a clutch shaft 100 carried by one of the frame members 50 and a portion 46 of one of the frame members 45. A spring 101 is secured at one end to an upwardly projecting lug 102 formed integral with the pawl, and at its opposite end to a portion of the main supporting frame, this spring operating to hold the pawl 99 in engagement with one of the notches 98 of the ratchet wheel 97, as illustrated in Fig. 12. The engagement of the pawl 99 with the ratchet wheel prevents the rotation of the ratchet wheel and of the pawl controlling member 95 formed integral therewith.

In Figs. 11 and 16 I have shown a supplemental pawl 103 pivotally mounted at 104 on the pawl 99, the pawl 103 having a forwardly projecting tooth 105 adapted to engage the notches 98 of the ratchet wheel 97. As stated above, the springs 91' normally hold the pawls in such a position that the rollers 87 are out of engagement with the lugs 86 carried by the constantly rotating clutch member, and therefore the power shaft 52 is not driven by the carrying wheel 54. When the operator desires to positively connect the power shaft to the driving wheel to raise or tilt the rake frame, he presses downwardly on a foot treadle 106 which is connected by means of a link 107 to an arm 107' carried by the clutch shaft 100 which carries the pawl 99. This operation raises the pawl 99, see Figs. 3, 11, 21 and 22, out of engagement with the ratchet wheel 97 acting against the spring 101, and at the same time the pawl 103 drops into engagement with one of the notches of the ratchet wheel and rotates the ratchet wheel through a small angle in an anti-clockwise direction (viewing Figs. 11 to 13). This rotation of the ratchet wheel also causes a similar rotation in the same direction of the pawl controlling member 95, and the rotation of this member by its engagement with the offset lugs 93 carried by the pawls 88, moves the pawls on their pivots 89 in an anti-clockwise direction, so that the rollers 87 will engage with the lugs 86 carried by the constantly rotating clutch member. After the rollers are in engagement with the lugs there is sufficient friction to retain them in engagement until they are withdrawn from engagement when it is desired to disconnect the power shaft from the driving wheel. This disconnection is made in the following manner: After the rake frame has been raised to the desired

which then drops into engagement with the ratchet wheel 97, and as this ratchet wheel is engaged by the pawl, the further rotation of the ratchet wheel is prevented and the pawls are again swung about their pivots 89, this time in a clockwise direction, out of engagement to a position in which the rollers 87 are out of engagement with the lugs 86. After they have been drawn from this engagement the springs 91' hold them in the position shown in Fig. 12, or in inoperative position.

In order to prevent injury to the machine and to automatically throw the power connections out of operation in case the operator forgets to remove his foot from the foot treadle, additional means has been provided to automatically disconnect the power shaft from the driving wheel. This means is illustrated in Fig. 11 and consists of a pawl 108 pivotally connected at 109 to the rake frame and disposed in a position to engage the ratchet wheel 97 when the rake frame has reached its upper limit of position. The rear end of the pawl 108 is slotted as shown at 110, a pin 111 extending through the slot and being secured to the rake frame; this pin and slot being provided to limit the movement of the pawl about its pivot. As illustrated in Fig. 11, the rear end of the pawl is heavier than the front end and the pawl therefore is normally disposed in the position shown in said figure. The action of the pawl 108 is exactly similar to that of the pawl 99 and the same results are obtained, and it is not believed to be necessary to explain this action in detail.

The connections between the power shaft 52 and the rake frame whereby the rake frame is raised and lowered, will next be described.

As shown in Figs. 2 and 3, the rake frame has secured thereto a plurality of vertical rack members 112, these members being spaced across the width of the frame. Each of these rack members consists of two racks 113 and 114, the teeth of the two racks being disposed in staggered relation, as clearly illustrated in Fig. 9. To cooperate with these racks in raising and lowering the frame, I have secured to the power shaft 52 a plurality of pairs of pinions 115 and 116, the teeth on these pinions also being disposed in staggered relation as shown in Figs. 9 and 10, and being adapted to engage the respective racks 113 and 114. The object of this particular form of rack and pinion is to provide greater strength, since in this way twice the amount of engagement between the racks and pinions is obtained over what would be obtained if a single rack and pinion were utilized. Referring to Fig. 26, it will also be seen that the double rack and pinion construction maintains the rake frame against lateral displacement. The

racks being tightly secured to the rake frame as illustrated in Fig. 11, and the pinions being rigidly secured to the shaft 52, it will be seen that as the shaft is rotated the rake frame will be positively raised and lowered.

Having described the connections for raising and lowering the rake frame, the means for retaining the rake frame in raised position and for retarding its descent, will next be described. This construction is illustrated more particularly in Figs. 21 to 25.

The means for retaining the rack in any desired position of elevation comprises a ratchet wheel 117 secured to the shaft 52 and having a series of teeth 118 adapted to be engaged by a pawl 119 pivoted on a transverse shaft 120 carried by the forwardly projecting frame members 50. A spring 121 engages the frame of the machine at one end and at its opposite end engages the pawl 119 and holds the pawl in engagement with the ratchet wheel. As the frame of the rack, therefore, is raised, the ratchet wheel is engaged by the pawl 119 and prevented from backward or reverse rotation, and in this way the rake is retained in any adjusted position. The pawl 119 is controlled by the operator on the seat 36 by means of a connecting rod 119' to a foot treadle 119''.

The shaft 52 also has secured thereto a brake drum 122 which is engaged by a brake band 123 secured at one end as shown at 124 to the transverse shaft 120, and having its opposite end connected by means of a bolt 125 to a laterally offset portion 126 formed integral with the pawl 119. From this arrangement it will be seen that a single means has been provided in which the ratchet pawl 119 through the connection 119' and foot treadle 119'' releases the ratchet wheel 117 and at the same time applies the brake on the brake drum 122 through the brake band 123 which is connected by the bolt 125 to the ratchet pawl 119.

From this description it will be seen that as the pawl 119 and its offset portion 126 are rotated on the shaft 120 to release the ratchet wheel and therefore the power shaft 52, in order to lower the rake frame, the free end of the brake band 123 will be moved in such a direction as to tighten the brake band on the drum 122, and cushion or retard the descent of the rake frame. A counterbalancing spring is also utilized to assist in the raising of the rake frame and to also retard its descent, this spring being shown particularly in Fig. 22. In this figure the counterbalancing spring 127 is adjustably connected at one end to a downwardly extending bracket 128 carried by the pole member 30, and at its opposite end is connected to a cable 129. The opposite end of this cable is wound upon a sleeve 130 secured to or formed integral with the ratchet wheel 117, and the end of this cable

is secured in any suitable manner to the ratchet wheel.

From this description and the showing in Fig. 22 it will be seen that the spring is utilized to assist in rotating the ratchet wheel in an anti-clockwise direction to raise the rake frame, and that this spring also retards the movement of the rake frame in the opposite direction, or in other words, retards its descent.

Having described the raising and lowering mechanism for the rake frame and the controlling means therefor, I will next describe the means for tilting the rake frame.

The object of tilting the rake frame is to increase the capacity of the tines. As a series of shocks is gathered they are forced by the forward movement of the tines and the engagement of their butts with the stubble, to the rear ends of the tines to a position adjacent the vertical portions 58 of the rake frame. In order to facilitate the gathering of a second series of shocks before dumping the first series, it is desirable that the butts of the shocks first gathered,— or those shocks at the rear ends of the tines,—be raised to a position out of engagement with the stubble, since the engagement of the butts with the stubble retards the propulsion of the machine through the field and requires a much greater draft; therefore, when the portion of the rake frame adjacent the vertical frame members 58 has been loaded with shocks, the rear end of the rake frame is raised to the intermediate dotted line position shown in Fig. 4.

The method of tilting the rake frame to this position and the construction by means of which it is tilted, will now be defined.

The rake frame has secured thereto a laterally projecting lug 131 (see Figs. 4 and 26), and this lug is engaged by the forward ends of chains 132 and 133. The chain 132 extends over a drum 134 carried by the shaft 52 and the chain 133 passes under the drum 134. The rear ends of the chains are connected to the front end of a link 135 which is pivoted at its rear end to a lever 136, the lever 136 being pivoted at 137 to the pipe 30. Intermediate the pivot point of the link 135 with the lever 136 and the pivot point 137 of the lever 136 with the pipe, said lever has pivotally connected therewith the front end of a link 138, the rear end of this link being pivoted at 139 to the lower end of a lever 140, which is pivotally connected at 141 to the pipe 30. In order to limit the forward movement of the lever 140 about the pivot 141, a bracket 142 is secured to the upper portion of the lever and is provided at its lower end with a stop member 143 adapted to engage with the pipe 30 when the lever 140 is moved about its pivot in an anti-clockwise direction. The upper end of the lever 140 has pivoted

thereto on a horizontal pivot 144 a sleeve 145 in which is journaled the rear end portion of a screw-threaded rod 146 which has secured to its rear end a hand wheel 147. 5 The front end portion of the rod 146 is screw threaded and engages a screw threaded bracket 148 carried by the rear end of a pipe 149. The front end of the pipe 149 is pivotally connected to a bracket 150 secured to the plate 62 which connects the upper ends of the inclined frame members 61. Thus it will be seen that rod 146 and pipe 149 form a connecting link between lever 140 and the rake frame. 10 Having described the construction of the tilting mechanism, the operation of this construction will now be briefly set forth. Assuming that the operator has gathered a plurality of shocks and these shocks are positioned at the rear ends of the tines 63, it then becomes desirable to raise the rear ends of the tines to the dotted line position shown in Fig. 4, the front ends of the tines being still engaged with the ground. In 20 order to raise the rear ends of the tines to this position, the operator throws in the clutch which connects the shaft 52 to the drive wheel thereby actuating the pinions 115 and 116 and by the engagement of these pinions with the racks 113 and 114, raising the rake frame. As the rake frame is raised, the lug 131 carrying the front ends of the chains 132 and 133 will also be raised, but if the rake is raised only to the intermediate 25 position shown in Fig. 4, the chain 133 will remain slack and the front end of the chain 132 will extend over the drum 134 as shown in Fig. 4, and will permit the front end of the rake to be tilted downwardly. Therefore, the rear end of the rake alone will be raised. In other words, the chain 133 controls the angularity of the tines 63 when the rake frame is in a raised position and the chain 132 controls the angularity of the 30 tines 63 when the frame is in a lowered position. In this connection it will also be noted that when the frame is raised from full line position to intermediate dotted line position shown in Fig. 4, the chain 132 becomes slack, releasing the tension of the rod 135 and through the connections 136, 138 and 140 the pipe 149 is permitted to move forwardly with the frame 58 into the forward dotted line position and thereby causing the forward ends of the tines to engage the ground. It will be further noted from Fig. 2 that the cable 76 shown on the left hand side is slack, thus permitting the rake frame proper to raise to the intermediate 35 dotted line position shown in Fig. 4 before the extensions start to swing in assuming the positions shown in Fig. 3. After the rake frame has been filled to capacity with shocks, the operator again throws in the clutch and raises the rake frame to the upper dotted line position shown in Fig. 4, swinging the extensions up into the positions shown in Fig. 3, and when the rake frame has assumed this position the chain 133 has been raised into contact with the drum 134 and has become taut, thereby exerting a forward pull on the link 135, lever 136, link 138, and lower end of the lever 140. This tilts the lever 140 about its pivot 141 and therefore pulls rearwardly on the pipe 149, 40 tilting the upper end of the rake frame rearwardly to the right hand dotted line position (Fig. 4). In this position the rear end of the rake is disposed in a plane below the front end of the rake thereby retaining the shocks in position on the rake tines. By means of the screw threaded adjustment between the rod 146 and the bracket 148, the amount of tilting may be varied to suit the 45 conditions.

The operations of the raising and lowering, tilting and steering mechanisms have been set forth in the foregoing specification after the respective descriptions of these constructions, and therefore a further statement regarding the various operations is not believed to be necessary. 50

From the above description of the construction of my improved shock gathering machine it will be seen that I have provided means for gathering a plurality of shocks on the rake frame, and means for raising the rear end of the rake frame to elevate these shocks out of contact with the stubble, after which a further number of shocks may be gathered to completely fill the forward end of the rake frame. After the rake frame is thus filled to capacity with shocks, the frame may be raised and tilted upwardly at the front to retain the shocks in position 55 thereon. By means of the construction described, these operations may be carried out with a minimum amount of manual labor and the shocks may be gathered, transported and deposited in a comparatively short time and with great rapidity and efficiency. The improved mounting for the steering and supporting wheel insures the proper steering of the device and also prevents the sudden turning of the wheel as the machine 60 is started forwardly or moved rearwardly. 65

The shock gatherer described above also embodies supplemental gathering means disposed outside the main wheels, these supplemental means being foldable upon the main frame of the gatherer, power connections being utilized to fold the supplemental rake frames. 70

While I have described one specific embodiment of my invention, it should be distinctly understood that the invention is capable of modification and that modifications and changes in the construction and arrangement of the various elements of the device may be made without departing from 75

the spirit and scope of the invention as expressed in the following claims:

1. In a shock gathering machine, a frame, a rake carried thereby, single means for first tilting said rake, and then raising said rake relative to said frame.
2. In a shock gathering machine, a frame, a rake carried thereby, and power operated means for tilting said rake relative to said frame prior to raising said rake.
3. In a shock gathering machine, a frame, a rake carried thereby, power actuated means for tilting said rake relative to said frame prior to raising said rake, and manually operated controlling means for said actuating means.
4. In a shock gathering machine, a frame, a rake carried thereby and having longitudinally extending tines, and power actuated means for raising said rake, the rear ends of said tines being raised prior to the raising of the front ends thereof.
5. In a shock gathering machine, a frame, a rake carried thereby and having longitudinally extending tines, power-actuated means for raising said rake, and connections between said power actuated means and said rake and between said rake and said frame whereby the rake is so raised that the rear ends of the tines are first raised and then the front ends of the tines are raised.
6. In a shock gathering machine, a frame, a rake carried thereby, power actuated means for raising said rake on said frame, and means pivotally mounted on said rake for automatically disconnecting said power-actuated means from the source of power as said rake reaches a predetermined height.
7. In a shock gathering machine, a frame, a rake carried thereby, power actuated means for raising said rake on said frame, and means loosely carried by said rake for automatically disconnecting said power actuated means from the source of power as said rake reaches a predetermined height.
8. In a shock gathering machine, a main shaft, a frame mounted on said main shaft, a rake frame adjustably carried by said shaft, power actuated means for vertically raising said rake frame with respect to said shaft, means for disconnecting said power actuated means from the source of power and means for retaining said rake in its raised position.
9. In a shock gathering machine, a frame, a rake carried thereby, power actuated means for raising said rake on said frame, means journaled on and carried by said rake for automatically disconnecting said power actuated means from the source of power as said rake reaches a predetermined height, and means for retaining said rake in its raised position.
10. In a shock gathering machine, a frame, a rake carried thereby, power actuated means for raising said rake on said frame, supplemental means for assisting said power actuated means in raising said rake, and means for automatically disconnecting said power actuated means from the source of power as said rake reaches a predetermined height.
11. In a shock gathering machine, a frame, a rake carried thereby, power actuated means for raising said rake on said frame, means for locking said rake in raised position, and single means for simultaneously releasing said locking means and retarding the descent of said rake.
12. In a shock gathering machine, a frame, a rake carried thereby, means for raising said rake on said frame, means for locking said rake in raised position, and single means for simultaneously releasing said locking means and retarding the descent of said rake.
13. In a shock gathering machine, a frame, a rake carried thereby, power actuated means for raising said rake, means for automatically disconnecting said last named means from the source of power as said rake reaches a predetermined height, means for locking said rake in raised position, and single means for simultaneously releasing said locking means and retarding the descent of said rake.
14. In a shock gathering machine, a frame, a rake frame carried thereby, a plurality of vertically disposed racks carried by said rake frame, and power actuated means for reciprocating said racks and rake frame with respect to said first named frame.
15. In a shock gathering machine, a frame, a rake frame carried thereby, a plurality of vertically disposed racks on said rake frame, a power shaft carried by said first named frame, a plurality of pinions carried by said power shaft and meshing with said racks, drive wheels supporting said first named frame, operative connections between said drive wheels and said power shaft including a clutch, and means for manually controlling said clutch to connect said driving wheels to said power shaft and to disconnect the same therefrom.
16. In a shock gathering machine, a frame, a rake frame carried thereby, a power shaft carried by said first named frame, carrying wheels for supporting said first named frame, clutch mechanism for connecting said power shaft and said carrying wheels, manually controlled means for operating said clutch mechanism, and means for operatively connecting said power shaft to said rake frame whereby said rake frame may be raised and lowered in a vertical line.
17. In a shock gathering machine, a main frame, a rake frame carried thereby, a plurality of pairs of racks carried by said rake frame, the racks of said pairs having their

teeth disposed in staggered relation, a power shaft carried by said main frame and having pinions meshing with said racks, and means for connecting said power shaft to a source of power and for disconnecting the same therefrom.

18. In a shock gathering machine, a main frame, a rake frame carried thereby, lever mechanism carried by said main frame and connected to said rake frame, means for raising and lowering said rake frame on said main frame, and means cooperating with said raising and lowering means and said lever mechanism for tilting said rake frame as said rake frame is raised and lowered on said main frame.

19. In a shock gathering machine, a frame, a rake frame carried thereby, means for raising and lowering said rake frame, lever mechanism carried by said main frame and operatively connected to said rake frame at the upper end thereof, and flexible means connected to said lever mechanism and to said rake frame adjacent the lower end thereof for operating said lever mechanism as said rake frame is raised.

20. In a shock gathering machine, a main frame, a rake frame carried thereby, a drum carried by said main frame, lever mechanism carried by said main frame and operatively connected to said rake frame, and flexible means connected to said rake frame extending on opposite sides of said drum carried by said main frame and connected to said lever mechanism for operating said lever mechanism as said rake frame is raised.

21. In a shock gathering machine, a frame, a rake frame carried thereby, means for raising and lowering said rake frame on said main frame, said rake frame including a vertical frame portion, lever mechanism carried by said main frame and connected to said vertical frame portion adjacent the upper end thereof, a stationary member carried by said main frame, and flexible means connected to said lever mechanism and extending on opposite sides of said stationary member and connected to said rake frame whereby as said rake frame is raised the lever mechanism will be operated to tilt said rake frame.

22. In a shock gathering machine, a main frame, a rake frame carried thereby, lever mechanism carried by said main frame and connected to said rake frame, means for raising and lowering said rake frame on said main frame and means carried by said main frame cooperating with said raising and lowering means and said lever mechanism for tilting said raking frame as said rake frame is raised and lowered on said main frame.

23. In a shock gathering machine, a main frame, a power shaft carried thereby, a rake

frame carried by said main frame, means for connecting said power shaft to said rake frame to raise said rake frame, and resilient means connected to said rake frame and said power shaft for assisting in rotating said power shaft in a direction to raise said rake frame.

24. In a shock gathering machine, a main frame, a rake frame carried thereby, a power shaft carried by said main frame, operative connections between said power shaft and said rake frame whereby as said shaft is rotated in a predetermined direction said rake frame is raised, and means for retarding the rotation of said power shaft in a direction to lower said rake frame.

25. In a shock gathering machine, a main frame, a rake frame carried thereby, a power shaft carried by said main frame, operative connections between said power shaft and said rake frame whereby as said shaft is rotated in a predetermined direction said rake frame is raised, and resilient means for retarding the rotation of said power shaft in a direction to lower said rake frame.

26. In a shock gathering machine, a main frame, a power shaft carried by said main frame, a ratchet wheel carried by said power shaft, a pawl cooperating with said ratchet wheel to prevent said power shaft from rotating in a predetermined direction, a rake frame carried by said power shaft, a brake band operatively connected to said main frame, and means for simultaneously releasing said ratchet wheel and tensioning said brake band on said main frame.

27. In a shock gathering machine, a main frame, a rake frame carried thereby and vertically adjustable thereon, supplemental rake frame members carried by said rake frame and foldable with respect thereto and power actuated means for folding said members.

28. In a shock gathering machine, a main frame, a rake frame carried thereby, supplemental rake frame members foldably connected to said rake frame, a power shaft carried by said main frame, and operative connections between said supplemental rake frame members and said power shaft whereby said power shaft may be connected to said members to fold said members on said rake frame.

29. In a shock gathering machine, a main frame, carrying wheels supporting said main frame, a rake frame carried by said main frame and disposed between said carrying wheels and supplemental rake frame members carried by and movable with respect to said main frame and disposed outside said carrying wheels and power actuated means for moving said supplemental members.

30. In a shock gathering machine, a main frame, carrying wheels supporting said main frame, a rake frame carried by said main

- frame and disposed between said carrying wheels, supplemental rake frame members foldably connected to said rake frame and disposed outside of said carrying wheels, 5 means for raising and lowering said rake frame and said supplemental rake frame members, and means for simultaneously folding said supplemental rake frame members as said rake frame is raised.
- 10 31. In a shock gathering machine, a main frame, a rake frame carried thereby, supplemental rake frame members carried by said rake frame and foldable with respect thereto, power actuated means for raising said 15 rake frame with respect to said main frame, and means for simultaneously folding said rake frame members as said rake frame is raised.
32. In a shock gathering machine, a frame, 20 a rake carried thereby and power actuated means for first tilting said rake and then simultaneously tilting and raising said rake.
33. In a shock gathering machine, a frame, 25 a rake carried thereby and power actuated means for first tilting said rake to a predetermined angularity and then simultaneously tilting and raising said rake.
34. In a shock gathering machine, a frame, 30 a rake carried thereby and power actuated means for first tilting said rake and then simultaneously tilting and raising said rake, and means for adjusting the angularity of said tilt.
35. In a shock gathering machine, a frame, 35 a rake carried thereby and power actuated means for first tilting said rake and then simultaneously tilting and raising said rake, and means for adjusting the angularity of said tilt during the tilting and raising of said rake.
36. In a shock gathering machine, a frame, 40 a rake carried thereby, supplemental rake frame members carried thereon and foldable with respect thereto, and power actuated means for simultaneously adjusting said rakes and folding said rakes and supplemental members.
37. In a shock gathering machine, a frame,
- a rake carried thereby, supplemental rake frame members carried thereon and foldable 50 with respect thereto, and power actuated means for simultaneously adjusting said rake and folding said rake frame supplemental members, and manually controlled means for adjusting the angularity of said rake. 55
38. In a shock gathering machine, a frame, a rake carried thereby, supplemental rake frame members carried thereon and foldable with respect thereto, and power actuated means for simultaneously adjusting said 60 rake and folding said rake frame supplemental members, and manually controlled means for adjusting the angularity of said rake during the folding of said supplemental members. 65
39. In a shock gathering machine, a frame, a rake carried thereby, supplemental rake frame members carried thereon and foldable with respect thereto, and power actuated means for tilting said rake to a predetermined 70 angularity, and means for simultaneously raising said rake and folding said supplemental members.
40. In a shock gathering machine, a frame, a rake carried thereby and power actuated 75 means for first tilting said rake and then simultaneously tilting and raising said rake, and manually controlled means for adjusting the angularity of said tilting.
41. In a shock gathering machine, a frame, 80 a rake carried thereby and power actuated means for first tilting said rake and then simultaneously tilting and raising said rake, and manually controlled means for adjusting the angularity of said tilting during the 85 tilting and raising of said rake.
42. In a shock gathering machine, a frame, a rake carried thereby, supplemental rake frame members carried thereon and foldable with respect thereto, power actuated means 90 for first tilting said rake and then simultaneously raising said rake and folding said supplemental members.

In testimony whereof I affix my signature.

CHARLES PEARSON.
